(57) **CLAIM**

The ornamental design for a semiconductor module, as shown and described.

DESCRIPTION

FIG. 1 is a front view of a semiconductor module showing our new design.

FIG. 2 is a rear view of the semiconductor module of FIG. 1.

FIG. 3 is a left side view of the semiconductor module of FIG. 1.

FIG. 4 is a right side view of the semiconductor module of FIG. 1.

FIG. 5 is a top view of the semiconductor module of FIG. 1. FIG. 6 is a bottom view of the semiconductor module of FIG. 1.

FIG. 7 is a front, right, and bottom perspective view of the semiconductor module of FIG. 1; and,

FIG. 8 is a rear, left, and top perspective view of the semiconductor module of FIG. 1.

The broken lines shown in the drawing views of FIGS. 1-8 form no part of the claimed design.
